UNITED STATES PATENT OFFICE

SAMUEL RUBEN, OF NEW ROCHELLE, NEW YORK, ASSIGNOR TO RUBEN PATENTS COMPANY, OF NEW ROCHELLE, NEW YORK, A CORPORATION OF DELAWARE

ELECTRICAL MICROPHONE

Application filed October 24, 1930. Serial No. 490,904.

This invention relates to an electric microphone, and more particularly it relates to a microphone functioning through contact resistance variations with pressure changes upon an electrode surface composed of vanadium pentoxide in contact with another electrode.

The object of the invention is the provision of a device of this type which is stable, operates with sensitivity and is low in cost of construction.

Reference is made to the microphone described in my United States Letters Patent 1,748,620, upon which the present invention is an improvement. I have found that fused vanadium pentoxide has pressure electrical resistance characteristics similar to those of cuprous oxide; it sensitively varies with pressure applied to its surface. This material can be used advantageously in an electric circuit to modulate a current in accordance with sound waves impressed upon a contacting electrode; also to produce audio frequency oscillations in a circuit inductively related to a microphone using an electrode base coated with this compound and connected in a direct current circuit. In varying the pressure between the vanadium pentoxide electrode and its contacting electrode, there is a change in the intermolecular contact at the junction between the electrodes; this causes a change in contact resistance of the oxide material. For effective operation the fused oxide layer must be formed integrally with the base material. The method of preparing the vanadium pentoxide is described in my co-pending application filed contemporaneously herewith, describing a resistance device.

For a better understanding of the invention reference is made to the accompanying drawing which represents one embodiment thereof in the form of a microphone having one electrode composed of a nickel base with a thin layer of vanadium pentoxide which is in contact with an opposing electrode. At 1 is a steel diaphragm constituting one electrode, 1a representing rubber blocks to damp the diaphragm vibrations. A stationary nickel plate, 2, has a layer of fused vanadium pentoxide 3, as the other electrode, the van-

dium pentoxide being in continuous surface contact with the steel electrode. These elements are enclosed in and supported by insulating members 5 and 6, the nickel plate 2, with its layer of vanadium pentoxide, being mounted on screw 4, supported in insulation member 6. A metal case 9, is used for enclosing the several elements, the mouthpiece is at 10, and the terminals of the two electrodes are respectively at 7 and 8.

In the operation of the microphone as shown, the initial resistance is the sum of the contact and internal resistances; but as pressure is applied to the contact area, the resistance at the junction between diaphragm 1 and vanadium pentoxide layer 3, decreases, permitting a corresponding increase of current flow through the device. The resistance material must be employed as a thin body, its brittleness, therefore, making its use as a layer on a conductive base advisable.

What I claim is:

1. A device for translating audio frequency oscillations into oscillations of like frequencies in an electrical circuit, which comprises a vibratory electrode in surface contact with vanadium pentoxide as a cooperating electrode, means for directing audio frequency oscillations upon one of said electrodes, means for supporting the electrodes, and means for protecting said electrodes from extraneous audio frequency oscillations.

2. A device for translating sound waves into oscillations of like frequency in an electrical circuit, which comprises a vibratory electrode in surface contact with a vanadium pentoxide cooperating electrode, means for directing sound waves upon the first mentioned electrode, means for supporting the electrodes, means for protecting said electrodes from extraneous sound waves, and means for oscillating the vibratory electrode by impressing thereon audio frequency oscillations from an electro-magnet.

3. A device for translating sound waves into electrical oscillations of like frequencies which comprises a vibratory electrode in surface contact with a cooperating vanadium pentoxide electrode, and means for support-

ing the electrodes, means for shielding said electrodes from extraneous sound waves and means for oscillating the vibratory electrode by impressing thereon audio frequency oscillations from an electro-magnet.

- 5 4. A device for translating audio frequency oscillations into oscillations of like frequencies in an electrical circuit, which comprises a vibratory electrode in surface contact with vanadium pentoxide as a co-operating electrode, means for damping the vibrations of the vibratory diaphragm, comprising rubber rings about the periphery of said diaphragm, means for directing audio frequency oscillations upon one of said electrodes, means for supporting the electrodes, and means for protecting said electrodes from extraneous audio frequency oscillations.
